Harold W. Hodgetts,

BY Harry W. Brown.

ATTORNEY.

UNITED STATES PATENT OFFICE.

HAROLD W. HODGETTS, OF SPRINGFIELD, MASSACHUSETTS, ASSIGNOR TO LEON J. HARLEY, JR., OF SPRINGFIELD, MASSACHUSETTS.

CASKET-HANDLE.

1,342,443.

Specification of Letters Patent. Patented June 8, 1920.

Application filed June 30, 1919. Serial No. 307,724.

To all whom it may concern:

Be it known that I, HAROLD W. HODGETTS, a citizen of the United States of America, residing at Springfield, in the county of 5 Hampden and Commonwealth of Massachusetts, have invented certain new and useful Improvements in Casket-Handles, of which the following as a specification.

This invention relates to improvements in 10 the construction of casket handles, in which the handle or bar portion is pivotally secured to a pair of plates that are secured to the side of the casket, usually by means of screws.

15 The primary object of my invention is to provide suitable means for rigidly securing the usual tubular bar against lateral movement in the socket portion of the arms that are pivotally connected to the attaching 20 plates on the side of the casket. At the present time it is usual to secure the bar to the sockets by means of a single screw. This is objectionable as it does not eliminate the relative movement between the bar and 25 the socket and results in lateral movements of the bar and arm causing an unsightly appearance. It has also been the practice to drive nails or staples through the soft metal of the socket and into the space between one wall of the socket and the opposite 30 portion of the wall of the bar.

35 My present invention resides broadly in stamping or crimping a portion of the reinforcing piece surrounding the perforation or opening of the plate of the socket, through which the handle passes, against the side of the tubular bar.

The accompanying drawings illustrate the objects and nature of the invention, in 40 which:

Figure 1 is a side elevational view showing the general elevational view of the usual casket-handle construction with the bar and attaching plates.

45 Fig. 2 is a transverse sectional view on the line 2—2 of Fig. 1 showing the usual tubular handle bar proper which is composed of thin metal, the reinforcing piece before crimping or bending the metal surrounding the perforated portion of the plate.

50 Fig. 3 is a view similar to Fig. 2, but showing the reinforcing piece of the arm crimped or bent inward against the side of the bar.

Fig. 4 shows a slight modification in which the reinforcing piece of the arm instead of being bent inward against the side of the bar, is crimped or bent laterally in order to shorten its length as will more fully 60 appear.

Fig. 5 is a transverse sectional view on the line 5—5 of Fig. 4.

Referring to the drawings in detail, 1 designates the tubular bar which is located 65 in and passes through the pivotal socket portion 2 of the arms 3, which are pivotally connected to the attaching plates 4 by means of the pins indicated at 5. Located in each of the arms 3 is the perforated reinforcing 70 plate 6 which comprises the rectangular opening 7 transverse to the plane thereof and through which the usual metallic tubular bar 1 passes. The plate 6 is secured in the arms 3 by flowing the metal around the 75 same as shown in Fig. 5 at 3', whereby these plates are permanently retained in position in the arms 2. As shown in Fig. 3, the side 6' which forms one side of the opening is bent or permanently crimped inward against 80 the wall of the metal tubing composing the bar 1. This crimped part forcibly drives the thin metal of the tubing inward against the wooden block 7' which fills the interior of the bar 1, whereby the bar is prevented from 85 slipping endwise through the openings in the plate 6, or in other words, it is frictionally held in place within the openings which pass through the plates 6 of the arms 3. The upper edge of the plate 6 is indicated at 6''. 90 The position of the lower edge of the plate 6 is spaced from the arms 3 as shown at 2''. The effect of bending this part of the plate 6 inward is to shorten the distance between the pivot 5 and the end of the plate. Should 95 it be desired to remove the handle, it is only necessary to pry or lift the crimped part 6' of the plate 6, away from the tubular bar 1. The plate 6 is understood as being fixed at its ends in the arm 3.

100 Fig. 2 shows the relation of the plate 6 and the side 6' to the bar 1 before the side is crimped or bent inward. Fig. 4 shows a slight modification in which that portion of the plate 6 surrounding the opening 7, instead of being bent inward as shown in Fig. 3, is twisted or curved sidewise, thereby shortening the distance between the end 6'' and the pivot 5. In order to loosen the tubular bar 1, the crimped part 6' is straight. 110

ened out as shown by the dotted lines 6⁴. It will be seen that the tubular bar 1 is rigidly secured in place by simply bending or crimping one side of the plate 6 surrounding the opening 7 in order to force the metal at that side of the opening in the plate against the tubular bar. The operation of securing the tubular bar in the openings of the bar 1 takes place after the bar 1 has been adjusted longitudinally in the openings of the arms 2.

It is to be understood that the term "plate" refers particularly to the part 6 which performs the purpose of a rib or strengthening element.

What I claim is:

1. In a casket handle construction, the combination with the tubular bar thereof, of a hanger arm, a flat one-piece rib or plate 20 having an opening therethrough and secured to the arm and having integral and bendable portions surrounding the opening through which the bar passes, said plate having one of its sides which surrounds the opening bent directly inward against the bar and with a permanent set, and transversely of the opening, whereby the bar is

frictionally retained against movement in the arm and relative to the rib or plate.

2. In a casket handle construction for securing the bar in place, the combination with the arm thereof, through which the usual metal tubular bar passes, of a flat one piece plate located in the arm and formed with an opening through the plane of the same and in which opening said bar is located, said bar being retained in a fixed position relative to the arm by crimping or forcing a part of the plate surrounding the opening against the metal tubular bar, whereby the bar and plate are held in frictional engagement with each other, as described.

3. In a casket handle construction for securing the bar in place, the combination with the usual metallic bar proper, of a 45 plate formed with an opening and through which the bar passes, means for securing the plate to the bar by shortening the distance between the ends of the arm by crimping the metal of the plate surrounding the opening 50 in opposite directions, whereby the bar is frictionally held in place in the plate.

HAROLD W. HODGETTS.
